UNITED STATES PATENT OFFICE.

JOSEPH W. WEISS, OF BALTIMORE, MARYLAND.

COLLAPSIBLE BOX.

1,146,115.

Specification of Letters Patent. Patented July 13, 1915.

Application filed February 17, 1914. Serial No. 819,144.

To all whom it may concern:

Be it known that I, JOSEPH W. WEISS, a citizen of the United States, and a resident of Baltimore, and State of Maryland, have 5 invented certain new and useful Improvements in Collapsible Boxes, of which the following is a specification.

This invention relates to collapsible boxes, particularly to boxes of this character which 10 are reinforced to withstand impact and rough handling.

In the manufacture of collapsible boxes, it is one of the primary considerations, aside from the features of collapsibility of the 15 box, to provide cheapness of construction and strength. In my prior Patent, Number 1,063,845, I have described and claimed a collapsible box of fibrous material in which a reinforcing fold is formed out of the material 20 of the box at the junction of the flaps and sides to strengthen the walls of the box and space them from the supporting surface, so that the impact is received by the layers of the folds instead of being received directly by the walls or sides proper. In the present invention, a construction is provided whereby the folds are made to encircle the corners of the box, and thus 25 further strengthen the same without the aid of auxiliary corner pieces such as described in my patent above mentioned.

In carrying out the invention, I make a double score at the junction of the sides of the box to form projecting ridges at the 30 junction of the sides. These ridges not only serve to form strengthening means for the box at its longitudinal edges, but also permit the folds to easily bend around the corners without disturbing the material to any 35 considerable extent.

In the drawings illustrating this invention, Figure 1 is a perspective view of the blank with the scoring and folding completed, previous to the joining of the free 40 edges of the sides. Fig. 2 is a perspective view illustrating the box as set up. Fig. 3 is a fragmental section taken along line 3—3 of Fig. 4. Fig. 4 is a fragmental section taken along line 4—4 of Fig. 2.

50 My improved collapsible box may be made of corrugated board, fiber board or any other board of fibrous material.

Referring in detail to the drawings, the box consists of the sides 10 and the end 55 flaps 11 which close the ends of the box after the same is set up. At the junction of

each pair of the sides are formed two longitudinal scores 12 and 13 between which is formed a projecting ridge 14 substantially U shape in section, the outer surface of 60 which extends at an angle to the joining sides. This projecting ridge serves to take up the shock and impact from the sides and forms a sort of cushion therefor. Between the sides and flaps is formed at each end of 65 the box, a continuous fold 15 which reinforces the ends of the box and also spans the corners and reinforces the same.

As will be noted, the ridges 14 relieve the sharpness of the corners of the box and permit the fold 15 to round the corners in a gradual curve 15^a, thus relieving the material of the fold from the strain which would otherwise develop in bending around a sharper corner. The folds are preferably 75 secured to the sides by suitable fasteners such as staples 16. However, it will be understood that these fastening means may be dispensed with, as, when the free edges of the sides are fastened together, the fold will 80 be held in place by the disposition of the material itself.

It will thus be seen that I have provided a collapsible box of fibrous material which is well reinforced and cushioned from impact and is withal cheaply manufactured and is practical in use. The entire box may be formed of one integral piece of material, portions of which accomplish all the required strengthening and cushioning func- 85 90 tions.

Having thus described my invention, I claim as new and desire to secure by Letters Patent:

1. A collapsible box of fibrous material 95 having sides and end flaps, a fold formed of the material of the box at the junction of the sides and flaps to reinforce the ends and corners of the box, and a rigid longitudinal fold formed of the material of the box for 100 reinforcing the longitudinal edges of the sides.

2. A collapsible box of fibrous material having sides and end flaps, a continuous reinforcing fold at the junction of the sides 105 and flaps, angular sections formed by parallel crimps between the adjacent sides at the corners, said folds spanning said angular sections.

3. A collapsible box of fibrous material 110 having sides and end flaps, a continuous reinforcing fold at the junction of the sides

- and flaps, **U** shaped angular sections formed by parallel crimps between the adjacent sides at the corners, said folds spanning said **U** shaped angular sections.
5. 4. A collapsible box having sides and end flaps, projecting ridges formed out of the material of the box at the junction of the sides, said ridges being separate from the sides by crimps and continuous folds formed out of the material of the box at the junction of the sides and flaps, said folds spanning the projecting ridges to form a gradual bend between the sides.
10. 5. A collapsible box having sides and end flaps, **U** shaped rigid projecting ridges formed out of the material of the box at the junction of the sides, and continuous folds formed out of the material of the box at the junction of the sides and flaps, said folds spanning the **U** shaped projecting ridges to form a gradual bend between the sides.
15. 6. A collapsible box formed of an integral sheet of fibrous material comprising side and end flaps, substantially **U** shaped projecting ridges connecting the sides and
20. 7. A collapsible box formed of an integral sheet of fibrous material comprising side and end flaps, substantially **U** shaped rigid projecting ridges connecting the sides and
25. 8. A collapsible box formed of an integral sheet of fibrous material comprising side and end flaps, substantially **U** shaped continuous folds at the junction of the sides and flaps, said folds spanning the projecting ridges and bending gradually from one to the other of the adjoining sides to reinforce and protect the corners of the box.
30. 9. A collapsible box formed of an integral sheet of fibrous material comprising side and end flaps, substantially **U** shaped continuous folds at the junction of the sides and flaps, said folds spanning the projecting ridges and bending gradually from one to the other of the adjoining sides to reinforce and protect the corners of the box.
35. 10. A collapsible box formed of an integral sheet of fibrous material comprising side and end flaps, substantially **U** shaped continuous folds at the junction of the sides and flaps, said folds spanning the projecting ridges and bending gradually from one to the other of the adjoining sides to reinforce and protect the corners of the box.
40. 11. A collapsible box formed of an integral sheet of fibrous material comprising side and end flaps, substantially **U** shaped continuous folds at the junction of the sides and flaps, said folds spanning the projecting ridges and bending gradually from one to the other of the adjoining sides to reinforce and protect the corners of the box.

Signed at New York city, in the county of New York, and State of New York, this 27th day of January A. D. 1914.

JOSEPH W. WEISS.
